MACHINE FOR THE MANUFACTURE OF
KNITTED FABRICS HAVING PLAIN
AND BACK STITCHESFrancisco Pladeveya Capdevila, Olot, Spain, as-
signor of one-half to Salvador Turull Fornells,
Mataro, Barcelona, Spain

Application September 24, 1952, Serial No. 311,261

Claims priority, application Spain
October 22, 1951

12 Claims. (Cl. 66—13)

1

The present invention relates to a new machine for the manufacture of knitted fabrics having plain and back stitches.

The object of this invention is to provide a machine for the manufacture of knitted fabrics of the kind set forth, which constitutes a noticeable simplification with respect to those known hitherto, making it possible to suppress one of the two co-axial cylinders the same are provided with, as well as the complications of centering and driving both the said needle cylinders. The present invention abolishes, furthermore, the well known double end latched needles which, even in case of being designed in the best manner, are always damaged in consequence of the hard working of the driving jacks thereof as they alternatively pull and push on their hooks to make them pass from one to the other of said cylinders within the respective grooves, thus giving rise to the consequential bluntness and wear and tear of the nibs of said hooks. In the new machine according to the invention, said needles may be improved so far that all the weak members they are at present provided with are omitted, either in the case of latched needles, or of hooked ones.

According to the invention, these objects are attained by the arrangement of a machine of the specified kind comprising a single needle cylinder which includes at least two sets of needles with the corresponding thread feeding mechanisms in combination with a deflection means for each set, said cylinder having peripheral longitudinal grooves each one thereof being provided with a pair of adjacent needles arranged side by side, radially with respect to said cylinder, and provided with special hooks the cavities of which eventually face and coincide with one another, said needles being longitudinally slideable with respect to one another and both of them with respect to the cylinder, having respective heels near to their lower ends, specially arranged to co-operate with axial cams which provide the vertical needle movements necessary for the working of the machine.

Of course, this arrangement may likewise extend to the improvement and simplification of the known flat frames type, for the manufacture of knitted fabrics having plain and back stitches, without substantially departing from the scope of the invention. The sole differentiating feature to be noted in this case is that the needle beds are fixed whilst the movable elements for the operation of the needles are the cams, which will be suitably mounted in adequate travelling slides.

2

In order to facilitate the explanation, this specification is accompanied by a set of drawings showing an embodiment of the invention, not restrictive of the character thereof, with reference to the following description.

In the drawings:

Fig. 1 is an elevation in diametral section of the part of the machine corresponding to its devices for the obtention of the knitted fabric, in 10 an embodiment comprising two sets of needles;

Fig. 2 is a plan view of the devices shown in Fig. 1;

Figs. 3 and 4 show the two kinds of needles to which likewise extends the present invention;

Fig. 5 is a lateral view of the special sinkers used in the machine in question;

Figs. 6 to 9 inclusive, show the diverse working positions of the needles in respective stages for the obtention of the stitches, for two different needles sets;

Fig. 10 indicates, in a developed manner, the working diagram of the machine, comprising the cams for the selection of the needles and for the operation of the sinkers, and

Fig. 11 is a very amplified view of the sample of the knitted fabric obtained with this machine on the basis of plain and back stitches.

In connection with the quoted figures a machine according to the present invention is described comprising two sets of needles for the obtention of the knitted fabric in both its mesh positions by means of a single thread guide for each set, but it must be understood that the machine in question may be likewise developed with greater number of needle sets and, furthermore, in such a way that the same be provided with more than one thread guide to insert in the knitted fabrics wefts having different color or characteristics to obtain color combinations or transverse bands depending on the operation of the automatic distribution devices, which are already common to the circular type frames for the manufacture of knitted fabrics.

Thus, the machine which is described includes 45 a platform 12 (Fig. 1) provided with an aperture 13 for the passage of the devices which will be described later and to allow the manipulation within the circle of needles when the machine has a fabric mounted thereon. Concentrically with said aperture there is a toothed ring 14 designed to receive the mechanical drive for rotating the needles cylinder and all the devices attached thereto.

Said cylinder is fixed by any conventional means 50 to the toothed ring 14, and is indicated by the

reference numeral 15, being provided with external longitudinal grooves 16 as it is common in the circular type knitting machines. In each one of said grooves there are mounted two needles 17 and 18, the one at the bottom of the groove and the other over the former, externally, in order that both the needles are longitudinally slideable with respect to one another and to the cylinder 15. The inner needle 17 is longer than the outer needle 18 and is provided with a heel 19 located in such a position that it cannot be reached by the lower end of the needle 18, not even in positions wherein their lower ends are nearer to each other. The heel 19 is specially arranged to co-operate with a set of axial cams 20 for the operation of the inner needles, said cams being mounted on a fixed external supporting ring 21. The outer needle 18 is provided with a similar heel 22, co-operating with a second set of axial cams 23 coaxial with the former and located in a higher position, within the same supporting ring 21 to which it is likewise secured.

The said needles are illustrated independently in Figs. 3 and 4, and as to their working ends for the formation of stitches they are constituted by curved edges 24 converging at the end of the needle with the other straight edge, in such a manner that when both the needles are coupled together in working position, said straight edges are in adjacent contact, whilst the curved edges 24 start from the junction line provided by the concurrence of the edges 25 and diverge until abutting on the corresponding inner and outer straight edges 26, of both the needles 17 and 18 and opposite to said line of concurrence. The edges 25 of both needles are interrupted near to the working end of the latter by a recess 27 directed towards the opposite edge 26 and the curved edge 24, thus forming a hook apt to eventually retain at least one mesh of the knitted fabric or even four meshes as it will be hereinafter described.

The needle cylinder 15 has coupled thereto a flange 28 with grooves 29 for the passage of the needles 17 and 18, and grooves 30 specially arranged to house radial sinkers 31 working in a synchronous way with respect to the motion of the needles by means of the action of a set of radial cams for each set of needles, said sets of cams being generally indicated in the figures by the reference numeral 32 and mounted, as it is common, at the back of a sinker ring 33 and acting upon these sinkers within notches 34 thereof. Said sinkers have a recess 35 (Fig. 5) serving as a support for the meshes previously formed with the object of allowing the formation of further loops, which recess has extensions 36 radially directed in both directions to retain the said meshes on each of the needle sets.

Each one of said sets is combined with a deflection means for the formed knitted fabric which is essential for the formation of the new loops and to determine the stripping off of the loops previously formed. These deflection means are constituted by wire or the like arcs 37 and 38, one for each needle set, curved in such a manner that its center is located on the axis of symmetry of the needles cylinder. One of said arcs has the task of separating the formed fabric outwardly with respect to the circle of needles, for which purpose it must be located within the piece of knitted fabric. Due to this fact, the ends of the same are bent towards the center thereof and secured on respective supporting members 39 extending downwardly within the needle cylinder 70 75

15 until reaching the level occupied by the platform 12 to which they are secured. The other arc 38 deflects the fabric in the contrary direction, that is to say, from the outside of the latter towards the axis of the machine and the ends thereof are curved outwardly (Fig. 2) extending up above the sinker ring to which they are fixed by intermediate members 40.

In the embodiment described in connection with the figures, only two deflection arcs are necessary, one of each kind for each needles set. In the embodiments wherein the machine is formed of more than two sets, said arcs will be arranged in an alternate distribution.

Each set of needles has its own weft feeding means which, in the present case, comprise a thread guide 41 for one set and 42 for the other respectively. The thread guide corresponding to the set of needles having the outer deflector arc is likewise mounted outwardly and fixed to the sinker ring of the machine on a support 43. The thread guide corresponding to the set having the inner deflector is likewise mounted on the inner side of a supporting member 44 which extends downwardly within the cylinder 15, being secured to the platform 12.

The operation of the machine in connection with the formation of the stitches is as follows:

In order to facilitate the explanation the sets of needles are given the reference numerals 45 and 46 and it is supposed that all the pairs of needles 17 and 18 have already mounted meshes and the knitted fabric thus formed is pulled by means of a conventional plying device not shown in the figures.

It is likewise supposed that a given pair of needles, taken as a starting point for the explanation, is located in the position indicated by the arrow 47 in Fig. 2. When the longitudinal series of meshes 48 (Figs. 6-9)—left device—mounted on the needle in question, comes into contact with the arc 37 the fabric is deflected outwardly as shown in Fig. 6, the last mesh of said series being retained in the recess 27 of the inner needle 17 whilst the outer needle 18 stays with its end slightly underneath. This stage of the formation of the stitch is shown in the figures by the position 49 occupied by the pair of needles taken as a reference.

At this time the heel 22 of needle 18 comes into engagement with the cam 50 for the elevation of the needles (Fig. 10) said needle 18 thereby rising and passing through the mesh 51. This operation is complemented by an advance and return movement of the sinkers 31 due to the presence of the incoming portions 52 of cam 32, the scope of said motion of the sinkers being to facilitate the passage of the needle 18 and to leave the mesh 51 in a propitious position for the further loop formation.

When the needles taken as a reference reach their highest position the devices of the machine are in the working stage represented in Fig. 7, wherein said needle has crossed the mesh 51 and rotated until facing the thread guide 41 which carries the thread 53 into the recess 27 of the former, to which working stage corresponds the position 54 of the figures.

The following steps for the formation of the stitches consist of lowering the needle 18 thus dragging along downwardly through the mesh 51 a second loop 55 formed by the thread 53, until reaching the stage indicated in Fig. 10 corresponding to the position 56, which is attained by means of the cam 57 for the lowering of the

needles, in co-operation with a safety cam 58 to prevent the upward rebound thereof, and a guide cam 59 to avoid the needle 18 being dragged due to friction during the movement of the other needle 17 in the same groove.

Finally, the last stage is reached, corresponding to the formation of the stitches constituted by mesh 51 and loop 55, consisting in the raising of the needles 17 until said mesh 51 is stripped off from the recess 27 attaining the stages of Fig. 9, corresponding to the position 60. This maneuver is performed by the heel 19 of needle 17 reaching the cam 61 to be raised, which is followed by the immediate lowering thereof produced by the cam 62, which movement finishes the cycle corresponding to the formation of a stitch in one of the directions.

It must be noted that the needle 18 after its downward motion to form the loop 55 does not recover its original level provided by the flat portion 63 of cam 50, but it remains in a slightly higher position according to the height of the guide cam 59. At the same time, the needle 17, of which the original height was determined by the guide cam 64, drops a little more until reaching the level of the portion 65 of the corresponding cast cam 61, the amounts of the said movements being the most suitable in order that after the described working stages the relative positions of the needles, as to their heights, result inverted with respect to those which had at the start of this working cycle, with the feature that the knitted fabric always stays mounted on the needles in the highest position.

This condition is obtained when the couple of needles taken as a reference reaches the position 66 corresponding to the passage of the said couple from one to the other of the needle sets of the frame: in the present case from set 45 to 46.

Starting from this moment the knitted fabric which already had passed from the arc 37 comes into contact with the other arc 38 which deflects it towards the axis of the frame, thus coming into the working stage of the right side of Fig. 6, corresponding to the position 67. Now the relative position of the fabric with respect to the needles is the same as formerly with the sole differentiating feature that both the needles stay in inverted positions.

Starting from this working stage, the same operations which already have taken place on the devices of the left side are now repeated at the right side of Figures 6-9 and in the same functional sequence, passing through positions 67, 68, 69 and 70 corresponding to said working stages and being equivalent to the former positions 49, 54, 56 and 60. For the purpose of obtaining said stages the frame is provided with a cam 71 for raising the needles 17, with guide cam 72 and a cam 73 for its further lowering, safety cam 74 to prevent the rebounding thereof and guide cams 64 and 65 to determine its positions. On the other hand, the axial cams set 23 comprises a couple of additional cams 75 and 76, respectively for the raising and lowering of the needles 18 for the purpose of causing the casting off of the meshes 77 and leaving the fabric fixed to the needles 18 through the loops 78 lastly formed within the set 46, in a similar manner to that performed formerly with the needles 17 of set 45.

The movement of the sinkers 31 in this second set is performed in a similar manner by means of the portions 79 and 80 of the radial cam 32.

Of course, this construction may be provided

with conventional suitable means to enable the formation of designs and fancy patterns within stitch and color combinations, by the adequate selection of the needles in the most convenient angular positions within the respective sets. In the Fig. 10, for example, the outline 81 indicates the position which a selecting wheel may occupy, in combination with respective cams to lower the selected needles, indicated by the reference numeral 82. Nevertheless, all these combinations are based upon a primitive fabric having plain and back stitches (Fig. 11), wherein are shown meshes 83 turned towards the outside of the fabric, and meshes 84 turned towards the inside of the same.

This invention, within its essential construction, may be carried into practice in other embodiments differing in detail from that given only by way of example in the preceding description and illustrative thereof, to which likewise extends the claimed protection. Thus, it may be manufactured in any shape and size, utilizing in the manufacture thereof the materials most suitable to each particular case of embodiment, combined in the most convenient way to reach the proposed end, all this being comprehended within the spirit and scope of the present claims.

Having now described and ascertained the nature of the present invention, I declare that what I claim as new and of my own invention and desire to secure by Letters Patent is:

1. A machine for making knitted fabrics having plain and back stitches comprising a cylinder having grooves therein for parallel needles and a flange provided with grooves for radial sinkers, said cylinder including at least two sets of needles with the needles of all of the sets being located within a circle, the even sets of needles having a knitted fabric deflection means associated therewith for deflecting the knitted fabric outwardly with respect to the needle circle, a weft feeding means located within the deflection means, the odd sets of needles having a fabric deflection means deflecting the knitted fabric inwardly with respect to the needle circle, a weft feeding means located exteriorly of the latter of said deflection means, the needles being mounted in pairs in each groove of said cylinder adjacent to each other radially thereto thus constituting inner and outer needles, each needle having a hook with the recesses of the needles in each groove facing each other and being eventually coincident, the needles being slidable longitudinally with respect to each other and both with respect to the cylinder, operation heels on the needles, the heels of the inner needles engaging axial cams located about the cylinder, and further axial cams located about the cylinder engageable with the heels of the inner needles.

2. A machine according to claim 1, characterized in that said weft feeding means comprises at least one thread guide for each needle set in alternative positions within the cylinder of the machine, which thread guide is placed in an outer position with respect to the circle of needles.

3. A machine according to claim 2, characterized in that said weft feeding means includes at least one thread guide for each set of needles in alternate positions within the cylinder of the machine, which thread guide is placed in an inner position with respect to the circle of needles and mounted on a supporting member which extends downwardly within said cylinder being se-

cured to the machine platform, said needle sets having inner thread guides being alternated with in the machine cylinder and intermediate with said needle sets having outer thread feeders.

4. A machine according to claim 1, characterized in that said knitted fabric deflector means is constituted, for each needle set, by a wire arc having the center of curvature thereof on the axis of the cylinder, covering a central angle of the needle circle which includes all the steps for the formation of a passage of meshes on one side of the knitted fabric, said deflection means being at a convenient height over sinkers to substantially tend to separate said knitted fabric in radial direction with respect to the circle of needles.

5. A machine according to claim 4, characterized in that each one of said wire arcs corresponding to respective needle sets having outer thread guides, are secured to fixed points of the machine and arranged in inner positions with respect to the circle of needles such as to substantially enable the inner needles to form new loops across meshes retained by outer needles, and the further separation of said meshes to leave the knitted fabric retained only by said inner needles.

6. A machine according to claim 5, characterized in that each one of said wire arcs corresponding to respective needle sets having inner thread guides, are secured to supporting members placed within the needle cylinder and extending downwardly thereof to the level of the machine platform to which they are secured, said arcs being disposed externally with respect to the circle of needles to substantially enable the outer needles to form new loops across meshes retained by inner needles, and the further separation of said meshes to leave the knitted fabric retained only by said outer needles.

7. A machine according to claim 1, characterized in that said needles arranged internally within said grooves are provided with a working end comprising a curved outline which starts from the inner edge of said needle and converges with the outer edge thereof at said end, and a recess in said outer straight edge, near to said curved outline to substantially form a hook apt to retain meshes of a knitted fabric under lateral tension in both directions.

8. A machine according to claim 1, characterized in that said needles, arranged externally within said grooves are provided with a working end comprising a curved outline which starts from the outer edge of the needle and converges with the inner straight edge thereof at said end and a recess in said inner straight edge near to its working end, directed towards the outer edge and towards said curved outline to substantially

form a hook apt to retain meshes of a knitted fabric mounted on said needles under lateral tension in both radial directions, said inner edge being susceptible of coinciding with the outer edge of the other needle within the same cylinder groove.

9. A machine according to claim 1, characterized in that one of said axial cams comprises a set of cams to produce the sequence of raising and lowering of the outer needles for the thread feeding and formation of new loops in angular positions comprehended within the needle sets having inner thread guides, and a further set of cams for the successive raising and lowering of said outer needles to remove the meshes of the preceding passage in angular positions comprehended within the needle sets having outer thread guides.

10. A machine according to claim 1, characterized in that the further axial cams comprise a set of cams to produce the successive raising and lowering of the inner needles in angular positions comprehended within the needle sets having inner thread guides and immediately after the formation of the stitch by the outer needles to remove the meshes of the preceding passage, and a set of cams to produce the successive raising and lowering of said inner needles for the thread feeding and formation of new loops in angular positions comprehended within needle sets having outer thread guides and previously to the position wherein the separation of the meshes by the outer needles takes place.

11. A machine according to claim 1, characterized in that said axial cams comprise needles guide cams between said cams for the thread feeding and formation of the new loops and for the separation of the loops of the preceding passage, the height of said guide cams before and after said passage for one of said ensembles being different and alternated with the heights of the passages corresponding to the other ensemble, to substantially allow the needles in each groove which are retaining meshes to be slightly higher than the other ones.

12. A machine according to claim 1, characterized in that the radial sinkers comprise a vertically downwards directed recess, starting from the upper edge thereof and near to the inner ends of the same, said recess including radially directed extensions to substantially allow the removing of the meshes in either direction.
